UNITED STATES PATENT OFFICE.

EDGAR S. MOULTON, OF CENTRAL CITY, COLORADO.

ROLLER-MILL.

No. 866,799.

Specification of Letters Patent.

Patented Sept. 24, 1907.

Application filed June 30, 1905. Serial No. 267,817.

To all whom it may concern:

Be it known that I, EDGAR S. MOULTON, a citizen of the United States, residing at Central City, in the county of Gilpin and State of Colorado, have invented 5 certain new and useful Improvements in Roller-Mills; and I do hereby declare the following to be a full, clear, and exact description of the invention, such as will enable others skilled in the art to which it appertains to make and use the same.

10 This invention relates to improvements in mills, and particularly to a roller mill for crushing ores.

One of the objects of the invention is the improvement of the construction of a mill employing two independently supported revoluble members, one surrounding 15 the other and driven at a different speed.

Another object of the invention is the improvement of the construction of a mill, which is provided with a grinding drum and an auxiliary wheel, the auxiliary wheel being supported in a peculiar manner and being 20 capable of traveling at a different speed from the grinding drum.

A further object of the invention is the production of 25 a mechanism composed of a minimum number of parts, and which is comparatively simple and inexpensive to construct.

With these and other objects in view, the invention consists of certain other novel constructions, combinations, and arrangements of parts, as will be hereinafter fully described, illustrated in the accompanying drawings, and more particularly pointed out in the claims 30 hereto appended.

In the drawings: Figure 1 is a vertical, longitudinal, sectional view of a mechanism constructed in accordance with my invention. Fig. 2 is a top plan view of 35 the mechanism depicted in Fig. 1. Fig. 3 is a vertical, sectional view taken on line 3, 3, Fig. 1, and looking in the direction of the arrow. Fig. 4 is a fragmentary view, in side elevation, of the mechanism showing the lower and upper casings. Fig. 5 is a fragmentary, sectional view of the mechanism taken on line 5, 5, Fig. 1. Fig. 6 is a view in side elevation of one of the bearing casings and the members positioned therein, which support one end of the shaft carrying the auxiliary wheel.

This mill is constructed of a drum and an auxiliary 40 wheel, 1 and 2, respectively, said drum and wheel being supported entirely independent of each other, and do not touch at any point. The principal idea is to have the ore crushed, as it passes through the space 3, Figs. 1 and 5, between the tires 4 and 5 carried by the 45 grinding drum 1 and auxiliary wheel 2, respectively. This space 3 can be regulated at will, by the raising or lowering of the boxes 6, and as the dirt immediately comes in contact with the screens 7, it will quickly pass out of the mill, as soon as it becomes fine enough to pass 50 through the screens. There will always be water enough in the lower portion of the mill to wash the

screens, so they will not clog; the amount of water which will remain in the mill will be preferably about four inches in the bottom and around the outer sides.

The drum 1 comprises sections 9 and 10, Fig. 1, fixedly secured together by suitable fastening means, as bolts 11, which are passed through parallel flanges 12, 12, formed upon the sections of the drum 1. The section 10 of the drum is provided with a rib or bead 13, preferably annular in shape, which is adapted to be 60 positioned within a similarly constructed groove formed upon the section 9. The screens 7 are held in place upon each of the sections of the drum, by suitable means, as blocks 14, which are preferably cast upon the sections. Each section of the drum is provided 65 with comparatively large openings in its sides, for the purpose hereinafter specified. Each section is provided with a primary, annular flange 15 and with an auxiliary flange 16. The drum 1 is mounted upon a frame 17 carried by the beams 18, 18. The frame 17 is provided 70 with substantially semi-cylindrical members 19, which form the bearing for the drum. The members 19 of the frame 17 engage the portion 20, constituting the hub, of the drum. Positioned within the frame 17 is the lower casing 8. The casing 8 is water tight, except at 75 the bottom where a discharge spout is located, and is preferably constructed of sections riveted or otherwise fixedly secured together. The lower casing 8 is provided with a discharge spout 21 to discharge finished material and water. The primary flanges 15 of the 80 drum 1 are positioned between the sides of the frame 17 and within the casing 8 for preventing dirt and liquid from running onto the hub portion of the drum. The flanges 15 also serve to positively retain the removable, upper casing 22 in position upon the drum 1 85 and the lower casing 8. Segmental bands 23 are positioned between the flanges of the drum and are removably secured, through the medium of horizontal extension 24, to the lower casing 8. Any suitable means 90 may be employed, as for instance, bolts 25, for securing the bands 23 in position. The auxiliary flanges 16 of the drum 1 engage the cut-out portions 26 formed upon the supporting frame 17.

Removably secured to the sides of the drum 1 are pulleys 27, 27. The pulleys 27 are preferably provided with integral extensions 28, preferably annular in shape, which engage the drum 1 and assist in supporting said pulleys, thereby removing considerable strain off of the fastening means, as bolts 29, which are employed for securing the pulleys to the drum. The 100 central opening in each of the pulleys 27 is of substantially the same dimensions as the openings in the side of the drum 1. The bolts 25 and the bands 23 retain the drum 1 in position upon the supporting frame, thereby preventing displacement of said drum while 105 said bands are in position upon the supporting frame 17. Two driving pulleys are preferably employed for the 110

reason that the power for driving the wheel is more evenly distributed, thereby obtaining a more satisfactory result than if only one pulley was employed, causing the strain to be exerted entirely on one side of the drum.

Upon suitable supporting means, as 30, there are positioned journal casings 31. A horizontal shaft 32 is positioned transversely of the drum 1 and the casings 31. The auxiliary wheel 2 is fixedly secured to shaft 10 32 within the drum 1. Fixedly secured to one end of the shaft 32 is a driving pulley or belt wheel 33. Power is applied to this wheel 33 for rotating the auxiliary wheel 2. The shaft 32 is positioned within the vertically movable boxes 6 mounted within the journal casings 31. Thin pieces of material 34, preferably wood, are positioned in the bottom of the journal casings 31, and support the boxes 6. The pieces 34 of wood can be removed as the tires 4 and 5 wear to allow wheel 2 to drop downward and to be kept always at approximately 20 the same distance from drum 1. In the upper portion of each of the journal casings 31, there is adjustably secured bolts 35. Positioned within each of the journal casings 31 is a follower 36, which engages the lower end of the bolt 35. Interposed between the upper face of 25 the blocks 6 and the lower face of the followers 36, is cushioning means, as springs 37. If a foreign object, as for instance, a piece of steel, should be deposited at 3 between the tires 4 and 5, the auxiliary wheel 2 will be permitted to rise through the medium of the cushioning means 37, so that damage will not be done to the 30 mechanism. As soon as the foreign object is removed from the machine, the springs will return the auxiliary wheel 2 to its proper position for crushing ores, as said springs are of sufficient strength to prevent wheel 2 from moving vertically under normal conditions, that 35 exist during the crushing of ores. By adjusting members 35, the followers 36 may be caused to move vertically within the journal casing 31. If the followers 36 are moved downward within said casing, the springs will 40 be compressed for exerting a greater pressure upon the slideable blocks 6 which are engaged by the shaft 32.

By inserting additional pieces 34 in the casings 31, the shaft 32 may be raised. The comparatively large openings in the sides of the drum 1, as well as pulleys 45 27, permit the vertical adjustment of the shaft 32 within the drum 1, as well as the positioning of the combined feed hopper and spout 38 within the drum 1.

The feed hopper 39 is removably secured to beams 40, 40 by means of integral extensions 41 and fastening 50 means, as bolts 42, or the like. Integral with the hopper 39 is the angular spout 43. The discharge end of the spout 43 is positioned contiguous to the space 3 formed between the tires 4 and 5. By means of the spout 43, the ore is discharged near that portion of the 55 revolute drum and wheel 2, where the grinding and crushing of the ores takes place. The comparatively large apertures in the pulleys 27 and the drum 1 permit the shaft 32 to be adjusted without interfering with the combined feed hopper and spout 38. Wedges 60 44, preferably formed of wood, are driven between the drum 1 and tire 4 for the purpose of holding said tire in position upon section 10 of said drum. The auxiliary or inner wheel 2 is formed of sections 2*, which are secured together by suitable fastening means, as 65 for instance, bolts 45.

Upon referring to Fig. 4, it is seen that the bottom of the lower casing 8 is sloping to spout 21, clearly shown in Figs. 3 and 4. The sloping structure of the bottom of the casing 8 facilitates the discharge of ores from the containing casing or receptacle 8 through the 70 spout 21.

The auxiliary wheel is revolved more rapidly than the drum. The auxiliary wheel 2 is secured off-center for the purpose of having the tires of the drum and wheel, at one point, secured close together for 75 producing the space 3 where the greatest crushing pressure is brought to bear upon the ores deposited within the drum by means of the combined feed hopper and spout 38. It will be obvious, owing to the sectional structure of the drum, that it will be 80 easy to separate the sections of the drum 1, if it is desired to replace the tire on the drum or auxiliary wheel.

The screens 7 are preferably formed of screen-wire. The screen-wire is cut to fit the openings and is placed 85 in the space against the fillet, cast all the way round. Screen frames 7* are placed in the opening against the screen-wire. The lugs 14, which are cast on the outside of the mill, project over the screen frames 7*. After the screen frames 7* are in place, provision is 90 made for space between lugs 14 and screen frames 7* to insert a wooden wedge, which is driven in tight, and which holds screen frame and the screen-wire firmly in place, and can not jar loose.

What I claim is:

1. In a mechanism of the class described, the combination with a supporting frame, of a lower casing positioned within said supporting frame, a drum carried by said supporting frame, said drum provided with a plurality of flanges upon each side, removable bands secured to said supporting frame and positioned between the flanged portions of said drum, and an auxiliary wheel positioned within said drum.

2. In a mechanism of the class described, the combination with a supporting frame, of a drum carried by said supporting frame, said drum provided with annular flanges formed upon its sides, a removable casing positioned between the flanged portion of said drum, a pulley removably secured to each side of said drum, and a revolute member positioned within said drum.

3. In a mechanism of the class described, the combination with a support, of a drum having a bearing formed on each end thereof carried by said support, removable fastening members, constituting bands secured to said support and partially surrounding the bearing formed on a 115 plurality of pulleys provided with central openings secured to the sides of said drum, and a revolute member positioned within said drum.

4. In a mechanism of the class described, the combination with a supporting frame, of a lower casing carried by said frame, a revolute grinding drum carried by said frame, annular flanges formed upon said drum, said flanges positioned within the lower casing, a casing positioned between said annular flanges, and a revolute member positioned within said drum.

5. In a mechanism of the class described, the combination with a support, of a revolute grinding drum carried by said support, said drum comprising sections, one of said sections provided with an annular groove, the other section provided with an annular bead adapted to fit into said groove when said sections are secured together, each section provided with a screen, annular flanges of different radius formed upon each side of said drum, said drum engaging said support between the flanges upon each side, removable fastening means carried by said support, and partially surrounding portions of said drum and positioned between the flanges upon the sides, and a revolute member positioned within said drum.

6. In a mechanism of the class described, the combination with a support, of a revolute grinding drum carried by said support, said drum provided with a pair of annular flanges upon each side thereof, the inner flanges being of a greater radius than the outer flanges, a removable casting positioned upon said support and engaging said drum between said inner flanges, and a revolute member positioned within said drum.
- 5 7. In a mechanism of the class described, the combination with a support, of a revolute, primary wheel carried by said support, a shaft positioned within said primary

wheel, an auxiliary wheel fixedly secured to said shaft, said auxiliary wheel comprising similarly constructed sections, and an inclosing member positioned upon the outer edge of said section.

In testimony whereof I affix my signature in presence of two witnesses.

EDGAR S. MOULTON.
